ABSTRACT: Vacuum deposition apparatus for operation at low deposition pressures contains an ion gun in a separate chamber maintained at a higher pressure required for the production of a glow discharge. The ion gun is supplied with an inert gas to maintain its pressure and the ions are emitted into the deposition vacuum chamber through a small port generally aligned toward the substrate. The ions are used to bombard the substrate to clean its surface prior to deposition, or may bombard the substrate during or after the deposition step to improve adherence of the deposited film on the substrate.

ION CLEANING AND VAPOR DEPOSITION

This application is a continuation of application Ser. No. 352,456, filed March 17, 1964 and now abandoned.

This invention relates to coating apparatus, and more particularly to novel and improved vacuum apparatus in which a substrate may be cleaned by ion bombardment and coated by vacuum deposition.

To achieve a strongly adherent film by vacuum deposition it is necessary that the surface of the substrate be free from all contaminants at the instant of deposition. Elaborate chemical and physical cleaning procedures are presently required to achieve this condition. The removal of contaminants from the substrate has been attempted by ion bombardment of the substrate with only varying degrees of success. This is due to the fact that ion bombardment must take place in a chamber that is maintained at a relatively high pressure, such as 10^{-2} mm of mercury or higher, whereas the vacuum deposition should take place in the chamber maintained at a relatively low pressure, such as 10^{-5} mm of mercury or lower. During the period between ion bombardment at the relatively high pressure and the evacuation of the chamber to the relatively low pressure, the substrate will again collect a contaminant film of oil, gas, oxide, etc.

Heretofore, the most successful vacuum deposition processes involve elaborate chemical cleaning of the substrate prior to its insertion in the vacuum chamber. The chemically cleaned substrate is then mounted within the chamber, the vacuum chamber is evacuated to pressure of the order of 10^{-2} mm of mercury, the substrate is bombarded with ions produced by a cold cathode discharge to remove as much contaminant as possible, the chamber is then evacuated to the lowest pressure obtainable, and finally the substrate is heated to a relatively high temperature (several hundred degrees centigrade) for a period of several hours to remove adsorbed gases and other contaminants which have accumulated during the period between the ion bombardment and the evacuation of the chamber to the vacuum deposition pressure. These elaborate procedures are time consuming, costly, not always effective, and impose serious limitations on the nature of the substrate.

In the present invention the substrate is not required to be subjected to elaborate chemical or physical cleaning prior to its insertion in the vacuum chamber. A substrate which has been cleaned with ordinary solvents and with ordinary precaution is attached to a support electrode in the chamber, the chamber is immediately evacuated to a relatively low pressure, such as 10^{-5} of mercury, and the substrate surface is cleaned of contaminants, without the application of externally applied heat, by ion bombardment immediately preceding, and during, the deposition of the coating. To achieve this ion bombardment at this relatively low pressure, an ion gun is inserted into the chamber. An inert gas, such as argon, is metered into the ion gun at a rate sufficient to permit the formation of a glow discharge within the gun, yet insufficient to raise the chamber pressure above that which is required for vacuum deposition.

Briefly described, this invention comprises a main vacuum chamber which is maintained at the relatively low pressure required for vacuum deposition. Inserted through the wall of the main chamber is an ion gun having a small hole or exit port in its cathode which is exposed to the main chamber. The ion gun is supplied with an inert gas at a rate sufficient to maintain the internal chamber of the ion gun at a pressure suitable for the formation of a glow discharge within the gun. Ions released through the exit port into the main vacuum chamber are rapidly accelerated toward the substrate because of a relatively high negative potential that is applied to the substrate support electrode. These high velocity ions bombard the substrate material and dislodge all contaminants from the surface. With proper design of the complete system, the main chamber can be maintained at a pressure low enough to provide a long molecular mean free path and at the same time a sufficiently intense ion beam or spray to decontaminate the substrate sur-

face. Vacuum deposition may take place during, or immediately after, the ion bombardment of the substrate, by resorting to conventional evaporation techniques.

One object of this invention is to provide vacuum deposition apparatus capable of cleaning and coating a substrate within a very short period of time.

Another object of this invention is to provide vacuum deposition apparatus capable of atomically cleaning a substrate and preventing contamination prior to vacuum deposition.

Other objects will become apparent from the detailed description and the drawing, in which the single figure is a sectional view of a vacuum chamber and ion gun assembly embodying this invention.

In the embodiment of this invention shown in the drawing, numeral 10 denotes a vacuum chamber which may be a suitable bell jar, or, as shown in the drawings, may be a glass T joint having an inside diameter of approximately six inches and an overall length of approximately 18 inches. One port of vacuum chamber 10 may be sealed with an end plate 12 through which is mounted a substrate mounting rod 14, which may be any electrically conductive material, such as aluminum. Since end plate 12 is electrically insulated from other components in the deposition equipment by the glass vacuum chamber 10, it is not essential that mounting rod 14 be insulated from end plate 12. However, during the vacuum deposition process, the internal walls of vacuum chamber 10 will become coated and may cause end plate 12 to be electrically conductive with other elements in the deposition equipment. Therefore, it is desirable that substrate mounting rod 14 be insulated from end plate 12 by a suitable insulator 16. Substrate 18 may be mounted within chamber 10 on mounting rod 14.

At the opposite port and sealing the end of chamber 10 is another end plate 20 to which is mounted an ion gun 22, a pair of electrically insulated conductors to supply electrical current to heater element 24, and a third electrically insulated conductor which is connected to the cathode 26 of ion gun 22.

The third port of vacuum chamber 10 is covered and sealed with an end plate 28, through which extends a pipe 30 connected to vacuum pump 32.

As previously explained, ion gun 22 extends through end plate 20 so that its cathode 26 is within vacuum chamber 10. Ion gun 22 may be constructed from any suitable electrically insulating material, such as glass tubing, and must have sufficient strength so that it can withstand low pressures. The end of the ion gun within vacuum chamber 10 is covered with an electrically conductive metallic cap or cathode electrode 26 which contains a small centrally located hole or exit port 27, the diameter of which is determined by the vacuum pump capacity, the desired chamber pressure and ion flux. In practice, this may be of the order of 0.020 inch. Extending through the central bore of the ion gun to within the distance of approximately $\frac{1}{4}$ inch of cathode 26 is an anode electrode 34 which may be a rod of any suitable electrically conductive material. While the principal requirement of the material of anode 34 is that it must be electrically conductive, consideration must be given to the thermal expansion properties of the anode since it must extend through, and be sealed to, the envelope of ion gun 22. In order to supply ion gun 22 with an inert gas, such as argon, a tubing may extend from ion gun 22 to a metering valve 36, which, as subsequently will be explained, is adjusted to provide ion gun 22 with a pressure suitable for the production of a glow discharge between anode 34 and cathode 26. The opposite end of metering valve 36 is connected to a source of inert gas.

In operation, a substrate 18 is washed to remove excessive contaminants and is mounted in vacuum chamber 10 on substrate mounting rod 14. Vacuum pump 32 is then started and vacuum chamber 10 is evacuated to a relatively low pressure suitable for vacuum deposition. This may be in the order of 10^{-4} mm of mercury, or lower. When the proper vacuum in chamber 10 is achieved, a potential of approximately +500 to

+1,000 volts is applied to anode terminal 38 through a current limiting resistor 43. A zero or ground potential is applied to cathode terminal 40, and a potential of approximately -4,000 volts is applied to terminal 42. While vacuum pump 32 is operating, the pressure in ion gun 22 is increased to proper ionization pressure by the use of metering valve 36 which is slightly opened to permit the entrance of an inert gas into ion gun 22.

This introduction of an inert gas will increase the pressure within the ion gun; however, because vacuum pump 32 is in operation and because the small exit port 27 in cathode electrode 26 restricts the flow of gas into vacuum chamber 10, chamber 10 can easily be maintained at a suitable vacuum deposition pressure. In order to produce a glow discharge between anode 34 and cathode 26 of ion gun 22, the pressure within the ion gun must be maintained at a relatively high pressure of approximately 10^{-3} to 10^{-2} mm of mercury. If desired, this pressure within ion gun 22 may be determined by connecting a suitable pressure gauge to the inner chamber or bore of ion gun 22, or may be more simply accomplished by merely increasing the flow of inert gas by the further opening of metering valve 36 until an anode current is observed on milliammeter 37, which is connected between anode 34 and its power source. When an anode current is observed, it is an indication that ionization within ion gun 22 has commenced and a current flow exists between anode 34 and cathode 26. Some of the positive ions produced in the gun escape through the exit port in cathode 26 and are accelerated toward the target substrate 18 because of the large negative potential applied to mounting rod 14. In general, these ions encounter little or no collisions with neutral gas molecules within vacuum chamber 10 because of the relatively low pressure, and as a consequence they acquire a very high velocity. When these ions strike the surface of substrate 18, their momentum and energy is transferred to molecules or atoms at the surface of the substrate, thus causing them to be ejected or sputtered from the surface. Any contaminant film on the surface of substrate 18 will thus be removed.

While substrate 18 is being cleaned by ion bombardment from ion gun 22, heater element 24 may be turned on so that sufficient heat is produced to vaporize a small amount of coating material which may be suspended directly from heater ele-

ment 24 or placed into very close contact with the heating element. When the coating material has been boiled and evaporated, metering valve 36 may be closed and all of the voltage potentials removed from their associated terminals.

5 The metallic vapor produced by the boiling of the coating material will then become evenly deposited upon the surface of the substrate 18.

It has been found that adherent films of aluminum upon glass microscope slides that have not been previously chemically cleaned, have been cleaned by ion bombardment and vapor-deposited within a total elapsed time of four minutes. This compares with a total elapsed time of several hours required by prior art methods.

10 It must be understood that various changes in configuration and arrangement of the various components of the equipment may be made without departing from the spirit of the invention.

I claim:

15 1. An ion bombardment and vacuum deposition apparatus comprising:

20 a vacuum chamber;
electrically conductive substrate mounting means extending through a wall of said chamber;

means for evacuating said chamber to a vacuum deposition pressure;

25 an ion bombardment gun having an anode electrode disposed within a housing and a cathode electrode forming a wall of said housing, said cathode electrode being located within said chamber and having an exit port to permit the escape of ions from said gun into said chamber;

a gaseous feed means into said housing for maintaining said ion bombardment gun at a suitable ionization pressure;

30 means for applying an ion accelerating electrical potential between the cathode electrode of said ion bombardment gun and said electrically conductive substrate mounting means; and

35 electrical heating means within said chamber for evaporating a coating material.

40 2. The apparatus claimed in claim 1, further including means for applying an electrical potential between the anode electrode and the cathode electrode of said ion bombardment gun.
